UNITED STATES PATENT OFFICE.

GEORGE W. SPAYD, OF PALMYRA, NEW JERSEY.

DESIGN FOR A PUZZLE-BOARD.

SPECIFICATION forming part of Design No. 19,756, dated April 8, 1890.

Application filed March 13, 1890. Serial No. 343,795. Term of patent 7 years.

To all whom it may concern:

Be it known that I, GEORGE W. SPAYD, a citizen of the United States, and a resident of Palmyra, Burlington county, New Jersey, 5 have invented a new and original Design for a Puzzle-Board, of which the following is a specification.

My design for a puzzle-board is fully shown in the accompanying drawing; and it consists 10 of the representation of a Maltese cross and a series of medallions 0, 1, 2, 3, 4, 5, 6, 7, 8, 9, 10, 11, and 12, the medallions 1, 2, 3, 4, 5, 6, 7, and 8 being arranged in the form of a square 15 outside of the representation of the Maltese cross, and the medallions 9, 10, 11, and 12 be-

ing arranged between the arms of said cross, while the medallion 0 constitutes the center of the cross.

I claim—

The design for a puzzle-board, substantially 20 as described, and as shown in the accompanying drawing.

In testimony whereof I have signed my name to this specification in the presence of two subscribing witnesses.

GEORGE W. SPAYD.
